COMBINED EARPHONE SUPPORT RACK AND LISTENING UNIT FOR STUDENTS

Melvin S. Majesty and Bettye G. Majesty, both of 3973 Navahoe Road, Cleveland, Ohio 44121

Filed Aug. 30, 1966, Ser. No. 3,656

Term of patent 14 years

(Cl. D33—3)

FIG. 1

FIG. 2

FIG. 3

FIG. 5

FIG. 1 is a perspective view of a combined ear phone support rack and listening unit for students showing our new design;

FIG. 2 is an elevation of FIG. 1, the broken line portions of earphones being included for illustrative purposes only;

FIG. 3 is a plan view of FIG. 2;

FIG. 4 is a section on line 4—4 of FIG. 2; and

FIG. 5 is a bottom plan view of FIG. 2.

We claim:

The ornamental design shown for a combined earphone support rack and listening unit for students, as shown and described.
